CHILD'S CHAIR

Nina A. Lebidine, 21 Randolph Road, Woodbury, N.J.
Filed Jan. 22, 1960, Ser. No. 59,140

Term of patent 3½ years

(Cl. D15—1)

The dominant features of my design reside in those portions shown in full lines on the drawing.

I claim:

The ornamental design for a child's chair, substantially as shown and described.
